UNITED STATES PATENT OFFICE.

CHARLES LOUIS BALDAUF, OF WEST HOBOKEN, NEW JERSEY, ASSIGNOR TO THOMAS NELSON & SONS, OF NEW YORK, N. Y., A CORPORATION OF NEW YORK.

LOOSE-LEAF BINDER.

1,344,934.

Specification of Letters Patent. Patented June 29, 1920.

Application filed August 1, 1919. Serial No. 314,609.

To all whom it may concern:

Be it known that I, CHARLES LOUIS BALDAUF, a citizen of the United States, residing in the town of West Hoboken, county of 5 Hudson, State of New Jersey, have invented new and useful Improvements in Loose-Leaf Binders, of which the following is a specification.

My invention relates to the art of binders 10 for loose-leaves, such as are commonly employed in ledgers, dictionaries and encyclopedias.

The principal object of my invention is to 15 provide an improvement on the arrangement of my Patent No. 1,071,500, whereby the two cover members of the binding, although made integral with a back portion as in the usual bookbinding, may be laid out flat on a plane surface and reassembled 20 again with maximum convenience.

A second object of my invention is to provide an improved arrangement of binder whereby a portion of the leaves may be removed and replaced again with the maximum 25 of convenience when it is desired to remove or insert a leaf.

The novel features of my invention are 30 pointed out with particularity in the appended claims, but the invention itself, together with further objects and advantages, will best be understood by reference to the following description taken in connection with the accompanying drawing, in which—

Figure 1 is a perspective view of a binder 35 according to my invention with the leaves inserted and locked therein and illustrating also the spanner by which the device is locked and unlocked.

Fig. 2 is a sectional view on the line 2—2 40 of Fig. 1.

Fig. 3 is a perspective view of the binder shown in Fig. 1, unlocked, the cover portions lying in the same plane and a portion of the leaves laid aside on my improved 45 arrangement of holding pins.

Fig. 4 is a detail view illustrating the convenient manner in which the parts of my binder can be reassembled.

Fig. 5 is a view similar to Fig. 2 illustrating means for holding the leaves tight in the binder when it is only partly full and also illustrating a different form of pins for use in transferring sheets.

Fig. 6 is a detail view illustrating part of 50 the arrangement of Fig. 5 as it appears

when filled to capacity with loose leaves or sheets.

As indicated in Fig. 1, my binder comprises covers 1 and 2 connected by a back 3. Fixed to the back 3 parallel to and adjacent the lines along which it is connected to the covers 1 and 2 are binding bars 4 and 5, respectively, said bars being longer than the back 3 and their ends being bent at right angles so that they may be made to overlap. Bar 4 terminates at each end in pairs of spaced fingers 6, 7, 8 and 9, the fingers 6 and 8 being shorter than fingers 7 and 9. The ends of bar 5 have threaded apertures therein for receiving screws such as 10, 70 whose heads are adapted to clamp the fingers 6, 7, 8 and 9 to hold the bars 4 and 5 in the position shown in Figs. 1 and 2.

The ends of the fingers of each pair being disconnected; the bodies of screws 10 can 75 readily slip into the slots between the fingers. Moreover, the fact that fingers 7 and 9 are longer than fingers 6 and 8, enables a person reassembling the device after it has been opened to readily engage the bodies of the 80 screws 10 by the projecting ends of fingers 7 and 9 so as to guide the screws between the pairs of fingers. This action is facilitated also by the arrangement shown, in which the longer fingers 7 and 9 are on the side of bar 85 4 adjacent the back 3. I find that I can readily adjust the parts into the position for locking when holding cover 1 by one hand, without needing to guide the fingers on the 90 pins by the other hand.

I prefer to provide the bars 4 and 5 with coöperating projections and hollow headed pins 11 and 12 respectively, similar to those shown in my said prior patent for holding the leaves in place in the binder. 95

For convenience in removing and replacing sheets which are not to be changed at the time of replacing a sheet or inserting one, I provide a bar 13 having apertures 15 therein, arranged to pass over the ends of 100 pins 12, and having pins 14 fixed thereto and adapted to project through the sheets to be bound, the sheet being provided with apertures to accommodate both sets of pins. The bar 13 and its pins 14 permit part of the 105 loose sheets to be separated from those on pins 12 and laid to one side without danger of the sheets removed sliding relatively to one another to bring the apertures therein out of alignment. The action of pins 14 in 110

maintaining the removed sheets in their original relative positions is clearly illustrated in Fig. 3. It will be seen that the ends of pins 14 can be reinserted in the holes provided therefor in the sheets remaining on pins 12, and that thereupon the sheets on pins 14 will slide back onto pins 12 without hindrance. The binder can then be reassembled as previously described and the parts locked in place.

In the modification illustrated in Figs. 5 and 6, I have threaded the central post 12' and have placed a nut 16 thereon adapted to be screwed down against bar 13 in order to clamp the leaves firmly in place when the binder contains only a fraction of its capacity of leaves. The binder is shown only partly filled in Fig. 5. It is evident that pins 14, as shown in Figs. 2 and 3, would prevent the desired action of the nut 16, and I prefer to use in this case telescoping pins, such as 14', fixed to the bar 13 and which not only permit a part of the sheets to be laid to one side when desired, but which also permit the nut 16 to act as above described.

The remainder of the parts of the device shown in Figs. 5 and 6 are as previously described in connection with Figs. 1 to 4 inclusive.

Having thus described my invention, I claim:

1. In a loose leaf binder, a frame comprising two members normally disposed oppositely and one of which has a leaf holding pin thereon, the ends of said members being bent so as to overlap, one of said ends being formed with spaced fingers of unequal length, and the end adapted to overlap said fingers having clamping means thereon, a part of which is adapted to slide between said fingers.

2. In a loose leaf binder, in combination a pair of covers, a back secured thereto, two members connected to said covers and back and normally disposed oppositely, one of said members having a leaf holding pin thereon, the ends of said members being bent so as to overlap, one of said ends being formed with spaced fingers of unequal length, and the end adapted to overlap said fingers having clamping means thereon a part of which is adapted to slide between said fingers, the longer of said fingers lying

adjacent said back when the fingers are in position to be clamped by said means.

3. A loose leaf binder comprising in combination a frame including two members normally disposed oppositely one of which has a set of leaf holding pins thereon, a back to which said members are connected, said members having ends arranged to overlap when in normal position, the ends of one of said members being formed with spaced fingers, and the ends of the other of said members having clamping means thereon arranged so that a part may pass readily into and out of the space between said fingers.

4. A loose leaf binder comprising in combination a frame including two members normally disposed oppositely one of which has a set of leaf holding pins thereon, a back to which said members are connected, said members having ends arranged to overlap when in normal position, the ends of one of said members being formed with spaced fingers, the ends of the other of said members having clamping means thereon arranged so that a part may pass readily into and out of the space between said fingers, and a bar having apertures adapted to receive said pins and having additional pins fixed thereon arranged to extend through leaves held by said first mentioned pins.

5. A loose leaf binder comprising in combination a frame including two members normally disposed oppositely one of which has a set of leaf holding pins thereon, a back to which said members are connected, said members having ends arranged to overlap when in normal position, the ends of one of said members being formed with spaced fingers and the ends of the other of said members having clamping means thereon arranged so that a part may pass readily into and out of the space between said fingers, a bar having apertures adapted to receive said pins and having additional pins fixed thereon arranged to extend through leaves held by said first mentioned pins, one of said first mentioned pins being threaded, an apertured bar through which said pins extend, and a nut on said threaded pin for holding said bar in juxtaposition to leaves on said pin.

CHARLES LOUIS BALDAUF.
